DESIGN FOR A GRINDING MACHINE

Milburn A. Hollengreen, Harold E. Balsiger, John A. Boller, and Robert S. Elberty, Jr., Waynesboro, Pa., assignors to Landis Tool Company, Waynesboro, Pa.

Application June 6, 1940, Serial No. 92,867

Term of patent 14 years

To all whom it may concern:

Be it known that we, Milburn A. Hollengreen, Harold E. Balsiger, John A. Boller and Robert S. Elberty, Jr., citizens of the United States of America, residing at Waynesboro, in the county of Franklin and State of Pennsylvania, have invented a new, original, and ornamental Design for a Grinding Machine, of which the following is a specification, reference being had to the accompanying drawing, forming part thereof.

Figure 1 is a front perspective view of a grinding machine showing our new design; and Figure 2 is a rear perspective view thereof.

We claim:

The ornamental design for a grinding machine, substantially as shown.

MILBURN A. HOLLENGREEN.

HAROLD E. BALSIGER.

JOHN A. BOLLER.

ROBERT S. ELBERTY, JR.
